COPYHOLDING DEVICE FOR TYPEWRITING MACHINES

Filed March 11, 1925

Inventor:
Joseph Simsbury
by D. C. Stickney
Attorney

UNITED STATES PATENT OFFICE.

JOSEPH LINDBURG, OF BROOKLYN, NEW YORK, ASSIGNOR TO UNDERWOOD TYPE-WRITER COMPANY, OF NEW YORK, N. Y., A CORPORATION OF DELAWARE.

COPYHOLDING DEVICE FOR TYPEWRITING MACHINES.

Application filed March 11, 1925. Serial No. 14,596.

This invention relates to copy-holder attachments for typewriters in which a copy-sheet is fed line by line past a guiding plate.

In the application of J. A. B. Smith, Serial No. 748,554, filed November 8, 1924, there is illustrated a copy-holder in which a copy-sheet is inserted around a cylinder and is fed line by line by means of co-operating feed-rolls, past a fixed guide plate at the 10 livery side of said cylinder.

In this invention, there is provided a sectional cylinder designed to grip a copy-sheet at the leading edge thereof, which copy-sheet is then wound around the cylinder to bring 15 into view fresh lines of copy past a line-finding device in front of the cylinder.

One of the features of this invention relates to means whereby the copy-sheet may be quickly handled, by inserting the leading edge of the sheet between two sections of the cylinder, one of which is rockably mounted and forms a gripping jaw which bears upon the fixed section of the cylinder to grip the sheet. The fixed section of the cylinder 25 is revolvably mounted upon brackets which may straddle the machine to raise the copy-holder near the eyes of the operator. The gripping jaw is normally held closed by the action of a spring and is provided with 30 mechanism whereby the jaw may be swung open by depressing a lever operatively connected to said jaw. There is provided a retaining spring to prevent accidental displacement of the cylinder, said spring being 35 shown in the form of a spider having prongs bearing upon the end of the cylinder.

Another feature of this invention relates to means for squaring the copy-sheet previous to gripping the same between the jaws. 40 To this end there is provided a step in the jaws which extends the full width of the cylinder and against which the leading edge of the copy-sheet is squared. The step in the jaws forms a straight edge which is 45 parallel to the guiding edge of the front plate and thus provides an aligning base line for the copy-sheet; the lines of print are presumably parallel to the leading edge.

Other features and advantages will hereinafter appear.

In the accompanying drawings—

Figure 1 is a fragmentary side view, in elevation, showing the copy-holder as ap-

plied to an Underwood combined typewriting and computing machine having a fan-fold attachment.

Figure 2 is a front view, in elevation, showing the copy-holder straddling the machine and the fan-fold attachment.

Figure 3 is a cross-sectional view through the line 3—3 of Figure 2, showing the gripping jaws in the open position.

Figure 4 is a diagrammatic view of the cylinder in its half turned position, showing the copy-sheet swung to the rear of the cylinder.

Figure 5 is an end view of the cylinder on the line 5—5 of Figure 2, showing the gripping jaw operating mechanism.

Figure 6 is a fragmentary plan view, showing the gripping jaw operating mechanism.

This invention is illustrated in connection with an Underwood combined typewriting and computing machine having a fan-fold attachment, such as that disclosed in the application of W. F. Helmond, Serial No. 609,560, filed December 29, 1922, in which the copy-holder is mounted considerably higher than the machine, straddling the machine and the fan-fold attachment in order to raise a copy-sheet 10 to a position in the path of the line of vision of the operator.

Said Underwood machine comprises a typewriter 11 mounted upon a computing machine (not shown) which is operatively connected to the typewriter by means of a selecting mechanism 12. At the rear of the machine there is provided a fan-fold attachment, which includes supporting brackets 13, a carbon carrier 14 and a handle 15 for operating the latter.

A cylinder 16 upon which the copy-sheet is wound is provided with a rockable section 17 extending longitudinally the full length of the cylinder. Said rockable section is built into the cylinder forming a part thereof and is mounted upon supporting studs 18 fast to plates 19 to which the cylinder is fast by means of screws 20.

The copy-sheet is gripped between the rockable section 17 and a flattened portion 21 of the cylinder 16. Said rockable section is operatively connected to a spring 22 which tends to keep the movable section in its closed position. In order to insert the copy-sheet between the two members 17 and

21 it will first be necessary to swing open the rockable section as shown in Figure 3, and to this end, mechanism is provided which includes a lever 23 rockably mounted 5 upon a stud 24 fast to the plate 19. The lever 23 is provided with a finger piece 25 forming an integral part thereof and is operatively connected to a stud 27 by means of a slot 26. The stud 27 is fast to the 10 rockable section 17 through a clearance slot 28 in the plate 19, and is provided with a groove 29 carrying the spring 22 which is held under tension by a stud 30 fast to the plate 19.

15 Having gripped the copy-sheet by its leading edge, the cylinder is then rotated by means of a finger-wheel 31 fast at the end of a shaft 32 upon which the cylinder is rotatably mounted. On the first half turn, the 20 cylinder is swung from a position shown in Figure 3 to that shown in Figure 4. At this position of the cylinder the copy-sheet is thrown backwardly over a guide plate 33 which is provided with a half round edge 34 to prevent damaging the copy-sheet. The guide plate 33 extends the full width of the cylinder and is formed half round to guide the copy-sheet close to the cylinder up to the line-finding edge 35 which in this 25 instance is the extreme edge of the plate 33, and is placed in front of the cylinder directly in the line of vision of the operative. The plate extends at the rear of the cylinder, upwardly and rearwardly, forming an 30 inclined portion 36, and terminates with the downwardly turned round edge 34. Supporting the plate 33 there are provided brackets 37 at the ends thereof, which brackets are fastened to the plate by means of 35 fasteners 38 and are in turn fastened to the supports 39 straddling the machine. As shown in the drawings the plate 33 may be removed from the main brackets by loosening the screws 40 normally holding the two 40 brackets together.

45 By further rotating the cylinder the first lines of copy will be brought to view past the finding edge 35 of the plate 33 as shown in Figure 5, and then successively new lines 50 of copy may be fed as needed, either by means of the finger-wheel 31 or by mechanism connecting the cylinder to another finger-wheel (not shown) but fully illustrated in said application of J. A. B. Smith. Said 55 mechanism comprises a pair of bevel gears 41 and a second pair of bevel gears operatively connecting the shaft 42 to a second shaft upon which a finger-wheel near the keyboard of the typewriter is mounted.

60 In order to square the sheet previous to winding it around the cylinder so that the lines of print upon the sheet will appear parallel to the edge 35 and thus facilitate the finding of the line being copied, there 65 is provided a longitudinal step 43 extending

the full length of the cylinder which serves as a straight edge against which the leading edge of the copy-sheet is located.

The cylinder is prevented from accidentally rotating by a spider-spring 44 at the end 70 of the cylinder, which spider may be mounted fast upon one of the supporting brackets 37 and held against rotation on a shaft 45 supporting the cylinder. The prongs of the spring 44 bear upon the plate 19, thereby 75 causing a retarding friction thereon and preventing the rotation of the cylinder unless this friction is overcome by a greater rotating force, such as may be exerted by the finger-wheels when operated to advance the 80 copy-sheet.

To facilitate the opening of the rockable section 17 and to prevent the cylinder from being rotated when depressing the finger piece 25 there is provided a second finger 85 piece 46 fast to the plate 19 by means of screws 47, said finger piece 47 serving as a backing or support to prevent the rotation of the cylinder when the finger piece 25 is 90 depressed.

It will be noted that means are provided in this invention to feed a copy-sheet around a cylinder to successively bring into view lines of the copy past a line finder, by winding the copy-sheet on the cylinder, and that 95 means are provided to square and grip the copy-sheet by its leading edge upon the cylinder.

Variations may be resorted to within the 100 scope of the invention, and portions of the improvements may be used without others.

Having thus described my invention, I claim:

1. A copy holder comprising a sectional cylinder with main and gripping sections, supports therefor in which the main section is pivoted, a plate rigidly attached to the end of the main section, the gripping section being pivoted on one side of said plate, and means on the other side of the plate for oscillating the gripping section. 105

2. A copy holder comprising a substantially solid sectional cylinder with main and gripping sections, supports therefor in which the main section is pivoted, one of said sections having a stop in its gripping face to square an inserted sheet preparatory for the gripping action, and means whereby the gripping section may be oscillated to receive and grip a sheet of paper inserted against said stop. 110

3. A copy holder comprising a cylinder divided into a main section and a gripping section, a plate rigidly attached to one end of the main section and pivotally carrying the gripping section, a hand lever pivoted on the outer side of the plate and connected to the gripping section for operating it on its pivot. 115

4. A copy holder comprising a cylinder 120

divided into a main section and a gripping section, supports for the cylinder, a plate on the end of the cylinder, a hand lever pivoted on the plate and connected to the gripping section for operating it, a finger piece rigid with the plate whereby oscillation of the gripping section without turning the cylinder is facilitated.

5. A copy holder comprising a substantial-
10 ly solid cylinder made up of a main section and a gripping section, supports for the cylinder and a pivoted connection between the main section and supports, a plate rigidly attached to the end of the main section
15 and on which the gripping section is pivoted, a hand lever pivoted on the exterior of the plate and connections between said lever and the gripping section whereby operation of the lever may separate the sec-
20 tions, and resilient means with connections to the plate and gripping section for gripping a sheet of paper between said sections.

6. A copy holder comprising a plate, a sectional cylinder on one side of the plate, and
25 means on the other side of the plate manually operable to operate the sections, said means including a spring to resiliently hold the sections in gripping relation.

7. A copy holder comprising a plate hav-
20 ing a slot therein, a sectional cylinder consist-
ing of a main section and a gripping sec-
tion on one side of the plate, and means on
the other side of the plate manually operable
25 to separate the sections, said means extend-
ing through said slot in the plate and includ-

ing means to resiliently hold the sections in gripping relation.

8. In a copy-holder including a cylinder and means for supporting said cylinder over a typewriting machine or the like, means for gripping a copy-sheet by its leading edge upon said cylinder, and means for squaring said copy-sheet by its leading edge.

9. In a copy-holder including a cylinder and means for supporting said cylinder over a typewriting machine or the like, means for gripping a copy-sheet by its leading edge upon said cylinder, and means for squaring said copy-sheet by its leading edge, said last-mentioned means including a slot in said cyl-
45 50 inder forming a grip for the copy-sheet and the bottom of the slot forming a straight surface parallel to an axle upon which the cylinder is rotatably mounted.

10. In a copy-holder including a cylinder and means for supporting said cylinder over a typewriting machine or the like, means for gripping a copy-sheet by its leading edge upon said cylinder, means for squaring said copy-sheet by its leading edge, said last-mentioned means including a slot in said cyl-
55 60 inder forming a grip for the copy-sheet and the bottom of the slot forming a straight surface parallel to an axle upon which the cylinder is rotatably mounted, and means for rotating the cylinder to wind the copy-
65 sheet therearound to successively bring into view new lines of copy, past a line-finding device in front of the cylinder.

JOSEPH LINDBURG.
